UNITED STATES PATENT OFFICE.

FREDERICK C. OVEPBURY, OF HILLSDALE, NEW JERSEY, ASSIGNOR TO THE FLINT-KOTE COMPANY, OF BOSTON, MASSACHUSETTS, A CORPORATION OF MASSACHUSETTS.

NAIL.

1,410,076.

Specification of Letters Patent. Patented Mar. 21, 1922.

Application filed July 24, 1920. Serial No. 398,683.

To all whom it may concern:

Be it known that I, FREDERICK C. OVEPBURY, a citizen of the United States, residing at Hillsdale, in the county of Bergen and State of New Jersey, have invented new and useful Improvements in Nails, of which the following is a specification.

In laying prepared roofing on foundations of concrete or Portland cement, such as sometimes are required in certain types of construction, considerable difficulty is experienced in securing the sheet roofing in place. When nails or screws, as ordinarily fashioned, are employed, they become loose and useless for the purpose for which they are employed.

The present invention has for its object, therefore, to produce a nail or fastening, which may be driven by means of a hammer through the sheet of roofing into the concrete foundation, and which is so formed that it may be rotated through a short arc and lock itself in place.

On the accompanying drawing,—
25 Figure 1 represents a side view of a nail embodying the invention.

Figure 2 illustrates the nail, when seen from a different angle.

Figure 3 represents a perspective view of 30 the nail.

Figure 4 shows a concrete foundation and a sheet of roofing material in section, and illustrates the nail in fixed position.

My improved nail may be made of wire, 35 and it has a cylindrical shank 10, terminating at its upper end in a head 11, having a narrow groove or slot 12, into which the end of a screw driver may be inserted for the purpose of partially rotating the nail. The 40 head is preferably flat as shown.

The lower end of the shank is tapered, to

provide two converging flat faces 13, 13, which meet to form a sharp edge 14, and the thus flattened end, when seen in face view, as in Figure 1, is shaped somewhat 45 like a spearhead, with the converging side edges 15, the recesses 16, and the abrupt lateral or transverse thick shoulders 17. A point is formed at the convergence of the flat faces 13 and the edges 15, which may 50 be either angular or rounded, as shown.

In using the nail, the following procedure is preferably followed. The cement foundation is poured or laid as at 20, and, just before it finally sets to a hard mass, and 55 while it is still to some extent "green", the sheets 21 of asphalt-saturated and coated fibrous roofing are laid thereon. Then the 60 nails are driven, by means of a hammer, through the sheets (usually at their overlapping edges) into the cement or concrete. This is easily done, as the latter is still 65 partially soft. A screw driver is inserted in the slot of the nail head, and is rotated through a short arc, usually about 90°, more 65 or less. The nail is thus forced around until the thick shoulders 17 lie under a solid body of the concrete or cement, and, when the latter sets solid, the nail is held rigidly in 70 position.

What I claim is:

A nail consisting of a non-threaded shank formed at one end with a slotted head, and having at its other end downwardly converging forces with downwardly converging 75 side edges and abrupt lateral shoulders projecting beyond the shank, substantially as described.

In testimony whereof I have affixed my signature.

FREDERICK C. OVEPBURY.
